Inventor

UNITED STATES PATENT OFFICE.

FRANK D. WINDELL, OF PHILADELPHIA, PENNSYLVANIA.

PLAYING-CARDS.

No. 922,370.

Specification of Letters Patent.

Patented May 18, 1909.

Application filed November 14, 1908. Serial No. 462,563.

To all whom it may concern:

Be it known that I, FRANK D. WINDELL, a citizen of the United States, residing in the city and county of Philadelphia, State of Pennsylvania, have invented new and useful Playing-Cards, of which the following is a specification.

My invention consists of say sixty cards having thereon representations of flags of 10 different colleges, numbers and letters, the cards being divided into say four groups numbered from one to fifteen, the suits representing different colleges according to the flags or colors thereof, and the letters in each 15 suit being disposed only on certain cards thereof, so that such letters spell the name of the colleges represented by the colors, one of the primary points of the game being the winning of the cards whose letters spell the 20 name of a college. Another point of the game is to play the cards so as to be the first to "finish" a college and prevent the opponents from playing to any advantage.

For the purpose of explaining the invention, the accompanying drawing illustrates a satisfactory reduction of the same to practice, but the important instrumentalities thereof may be varied, and so it is to be understood that the invention is not limited to 30 the specific arrangement and organization shown and described.

Figures 1 and 2 represent face views of different cards comprising my invention. Fig. 3 represents a face view of a group of 35 other cards of the game.

Similar letters of reference indicate corresponding parts in the figures.

Referring to the drawing: A designates a number of cards comprising members of a 40 set or pack of sixty cards. Each card has thereon the representation B of the flag of a college, and the pack is divided, in the present instance, into groups or suits for four colleges, viz;—Penn. (University of Pennsylvania), Cornell, Princeton and Yale, the colors being respectively, red and blue, red and white, orange or yellow and black, and blue, but I do not limit myself to said colleges, as others may be selected, as may be 45 also other educational institutions. Each card has thereon a numeral C, and certain cards have letters of the alphabet D thereon, the numerals ranging from one to fifteen for each group, and the letters in each suit being 50 such that all of the letters in any one suit

spell the name of the college represented by the colors thereof.

One of the rules for playing the game is as follows:—Five cards are dealt to each player and five to the table. The dealer turns the 60 cards in the "field" face up. The player to the left of the dealer examines his hand and plays a card upon one or more cards in the field, the total value of which is the same as the card played. For example: player holds 65 a 13; he can play it

Upon a	13
Or upon 9 and 4	13
Or upon 7, 5 and 1	13

70

or upon any combination of cards in the field, the sum of the numbers upon which equals 13. He then takes up the card or cards in the field upon which he has played, and the card he has played, and deposits in front of 75 him the lettered cards of the college he is playing for. The other cards are placed to one side in a pile called the "stack", to be shuffled and dealt again as soon as the original pack is exhausted. A player keeps on 80 playing until he cannot "match" or play the proper corresponding card or combination of cards in the "field", and then deposits one card in the field. If in the beginning of his play he cannot match any card or combination of cards in the field, he simply deposits 85 one card in the field. The player to the left now proceeds with the game.

As soon as a player exhausts all of his cards in his hand, another hand of five cards is 90 given him.

When the original pack is exhausted, the cards in the "stack" are shuffled and dealt as required, a new "stack" being formed continuously as the game proceeds.

As for scoring, the first player to secure all the letters spelling the name of the college he is playing for, shouts the name of the college and receives five points. The cards, however, must all be the same suit. His hand, together with all the cards before him, is then placed in the "stack", and the game proceeds until another player has finished, and the second player to finish is credited with 100 three points.

Of course, there will be rules for dealing, selection of a college for which one plays, partners, etc.

The game will be found to be interesting, 110 entertaining, instructive and amusing.

Having thus described my invention, what I claim as new and desire to secure by Letters Patent, is:—

1. A set of cards comprising a plurality of groups containing thereon respectively representations of the flags or colors of colleges, and certain cards of each group bearing letters of the alphabet, which letters of each group taken together are adapted to spell the name of the college represented by the color or flag of the group.
- 10 2. A set of cards divided into groups con-

taining thereon respectively representations of the flags or colors of colleges, and on certain cards of each group letters of the alphabet, which letters of each group taken together are adapted to spell the name of the college represented by the colors or flags of the group, the cards comprising each group having consecutive numbers thereon.
